(57) **CLAIM**

The ornamental design for a guide member for a lace tightening device as shown and described.

DESCRIPTION

FIG. 1.1 is a perspective view of a first embodiment of the guide member for a lace tightening device;

FIG. 1.2 is a front view of the first embodiment of the guide member for a lace tightening device;

FIG. 1.3 is a back view of the first embodiment of the guide member for a lace tightening device;

FIG. 1.4 is a first side view of the first embodiment of the guide member for a lace tightening device;

FIG. 1.5 is a second side view of the first embodiment of the guide member for a lace tightening device;

FIG. 1.6 is a top view of the first embodiment of the guide member for a lace tightening device;

FIG. 1.7 is a bottom view of the first embodiment of the guide member for a lace tightening device;

FIG. 1.8 is an exploded perspective view of the first embodiment of the guide member for a lace tightening device showing a detachment of the guide member from a post;

FIG. 2.1 is a perspective view of a second embodiment of the guide member for a lace tightening device;

FIG. 2.2 is a front view of the second embodiment of the guide member for a lace tightening device;

FIG. 2.3 is a back view of the second embodiment of the guide member for a lace tightening device;

FIG. 2.4 is a first side view of the second embodiment of the guide member for a lace tightening device;

FIG. 2.5 is a second side view of the second embodiment of the guide member for a lace tightening device;

(Continued)

FIG. 2.6 is a top view of the second embodiment of the guide member for a lace tightening device;
 FIG. 2.7 is a bottom view of the second embodiment of the guide member for a lace tightening device.
 The broken lines in FIGS. 1.7 and 2.7 represent a bottom portion of the guide member that forms no part of the claim;
 The broken lines in FIGS. 2.1-2.6 represent a spring component that forms no part of the claim.
